SUPPORT

Filed Oct. 1, 1945

Patented Oct. 8, 1946

2,408,719

To members of the public who are engaged in the construction and repair of buildings, and especially to those engaged in painting and repairing the interior of buildings, it is known that it is often necessary to support a scaffold or the like from the rafters or other beams in a building. It is also known that it is often necessary to support a scaffold or the like from the rafters or other beams in a building. It is also known that it is often necessary to support a scaffold or the like from the rafters or other beams in a building.

UNITED STATES PATENT OFFICE

2,408,719

SUPPORT

Vardy M. Abernethy, Forest City, N. C.

Application October 1, 1945, Serial No. 619,545

1 Claim. (Cl. 304—19)

1

This invention relates to a support, and more especially to a support adapted to suspend scaffolds and the like from the rafters or other beams in a building; said support having means which, by the weight applied to the support, serves to embed a pair of prongs into the rafter and whereby the greater the downward pull applied to the support, the greater the gripping action it will exert upon the rafter or beam from which it is suspended.

Heretofore, in painting and otherwise repairing the interior of buildings, it has been quite a problem to suspend a scaffold in close proximity to the underneath side of the roof for applying a coat of paint to the rafters and the sheeting supported by the rafters. It has been the custom to bore holes in the roof and suspend rods, pipes and the like from the top surface of the roof for supporting a painting scaffold below the interior surface of the roof. Then, after the painting job is completed, it has been necessary to repair the roof, thus resulting in leaks occurring at these repair points.

It is an object of this invention to provide a support and whereby a plurality of these supports can be provided for engaging a plurality of the rafters or roof-supporting beams of the building for supporting a scaffold near the lower end or ends of the supports and whereby the weight of the scaffold will cause the prongs on the upper end of these supports to embed themselves in the sides of the rafters and weight applied to the scaffold will cause these prongs to sink more deeply into the rafter, thus insuring a hold upon the rafters which will not, under any circumstances, come loose until all weight is removed from the support and, when all weight is removed from the supports, they are easily removed from the rafters to which they have been affixed.

It is another object of this invention to provide a support adapted to engage opposed sides of roof-supporting beams, such as rafters and the like, and whereby the support has a pair of pivoted prongs on its upper end so that where the rafter is out of reach, the support can be inserted against one side of the rafter, that is one prong can be placed against one side of the rafter and a slight downward and lateral pull will cause the other prong to engage the opposed side of the rafter and a further application of weight or downward pull to the support will cause the points of the prongs to embed themselves in the sides of the rafter to firmly secure the supports thereto, each of said supports having a hook on its lower end for receiving a scantling for sup-

2

porting scaffolding and the like. The supports can also be suspended from I-beams.

Some of the objects of the invention having been stated, other objects will appear as the description proceeds when taken in connection with the accompanying drawing in which:

Figure 1 is a front elevation of one of the supports showing it ready to be attached to a rafter or beam in a building;

10 Figure 2 is a side elevation of the support shown in Figure 1, omitting the beam, and looking at the left hand side of Figure 1;

15 Figure 3 is an enlarged detailed view of the upper portion of Figure 1 and showing the prongs of the support embedded in the rafter or beam;

Figure 4 is a side elevation of the two nearest supports of four supports secured to the rafters of the roof of a building and showing the scaffold supported thereby.

20 Referring more specifically to the drawing, the numeral 10 indicates an elongated pipe, rod and the like which has a conventional coupling 11 threadably or otherwise secured on the lower end thereof. A sleeve 12 is rotatably and slidably mounted on the pipe 10 and has an outwardly and upwardly projecting prong 13 secured thereto by welding or otherwise, said prong being adapted to support a suitable scantling such as 14 indicated in Figure 4. There are usually four 25 of these supports secured in a quadrangle and a pair of scantlings 14 extending between the two proximate supports with a floor 15 being adapted to be laid thereon to serve as a scaffold.

30 The upper portion of the pipes 10 has slidably mounted thereon a sleeve 16 which is limited in its downward movement by a pin 17 suitably secured in the pipe 10 and projecting outwardly therefrom. This sleeve 16 has a pair of outwardly and oppositely projecting prongs 18 and 19

35 to the outer end of which are pivoted as at 20 and 21 the lower ends of dogs 22 and 23 which are pivoted as at 24 and 25 to the outer ends of links 26 and 27. These links have a plurality of holes 28 and 29, respectively, therein, in any one 40 of which, the pivot bolts 24 and 25 may be mounted. These bolts 24 and 25 penetrate one of the holes 28 or 29 in the links 26 and 27 and also penetrate a suitable hole through the intermediate portion of the dogs 22 and 23.

45 The proximate ends of links 26 and 27 are pivoted as at 34 to the upper end of pipe 10. The upper ends of the dogs 22 and 23 have pointed portions 30 and 31 which are adapted to be embedded in a beam such as rafters 32 which are 50 adapted to support sheeting 33 of the roof of a

building. These prongs 30 and 31 may likewise be secured to horizontal beams in a building even though there is no obstruction supported by the upper edge of the beams; but they are especially adaptable for securing to the rafters of a building without disturbing the roof supported by the rafters.

If it is desired to attach four of these supports to the rafters of a building, that is, two supports in spaced relation attached to each rafter, it is only necessary that the operator seize the lower end of the pipe 10 and project the support up to where, say, one of the prongs 30 or 31 engages one side of the rafter.

By a downward and lateral pull exerted on the pipe 10, the pipe 10 will slide downwardly in sleeve 16 and this will pull the inner ends of the links 26 and 27 downwardly which will cause the points 30 and 31 to both engage and become embedded in the opposed surfaces of the rafters 32. When sufficient weight has been applied to the supports to cause them to be firmly embedded in the sides of the rafter, then the sleeve 12 can be rotated to the proper position to receive the scantlings or beams 14 and a suitable floor 15 can be supported by the beams or scantlings 14.

These pipes 10 can be any desired length, that is of a length to support a man so he can reach the roof structure comprising rafters 32 and 33, or, if desired, to use and support another object a much greater distance below the roof 33, then these pipes 10 can be of any desired length to provide a scaffold or support at any desired distance below the roof structure. For example, one or more of these supports could be attached to the rafters or other cross beams in a building and a suitable hoist could be attached to the lower ends thereof and it could serve as a support for a

5 hoist, or overhead machinery, or for a variety of uses.

In the drawing and specification there has been set forth a preferred embodiment of the invention, and although specific terms are employed, they are used in a generic and descriptive sense only, and not for purposes of limitation, the scope of the invention being defined in the claim.

I claim:

10 A support adapted to be secured to opposed sides of a rafter or other beam in a building comprising an elongated shank, means on the lower end of the shank for supporting an object, a sleeve slidably mounted near the upper end of the shank, a pair of dogs having their lower ends pivotally secured to opposed sides of the sleeve, a pair of links pivotally secured to the upper end of the shank at one end and having their other ends pivotally secured to an intermediate portion of said dogs, the upper ends of the dogs being turned inwardly and pointed towards each other and terminating in a sharp point and being adapted to engage and embed themselves in opposed sides of the beam when applied to a beam and downward pressure is applied to the shank, a stop on the shank to limit downward movement of the sleeve, said sleeve normally resting by gravity on said stop to cause the pointed ends of said dogs to be widely separated, lateral pressure on the shank serving to embed the pointed upper end of one of the dogs in one side of the rafter or beam so that a slight downward pull on the shank will move the pointed end of the other dog against the other side of the rafter or beam, and further downward pressure on the shank will embed the pointed ends of both dogs further in the rafter or beam.
